Patented May 9, 1922.

UNITED STATES PATENT OFFICE.

HARRY A. DOUGLAS, OF BRONSON, MICHIGAN.

LAMP.

1,415,087.

Specification of Letters Patent. Patented May 9, 1922.

Application filed April 4, 1921. Serial No. 458,554.

To all whom it may concern:

Be it known that I, HARRY A. DOUGLAS, citizen of the United States, residing at Bronson, in the county of Branch and State 5 of Michigan, have invented a certain new and useful Improvement in Lamps, of which the following is a full, clear, concise, and exact description.

My invention relates to lamps and is of 10 particular utility when embodied in a portable electric lamp. The lamp of my invention preferably includes a handle by which it may be carried and manipulated; a lighting element, such as includes an incandescent lamp bulb, carried by said handle and a casing for the lighting element also carried by the handle and formed with a closure to protect the lighting element when the lamp is not in use, this closure portion 15 being preferably in the form of a concave reflector that functions as such when it is adjusted to open the aforesaid casing. An electric lamp thus constructed is of particular service when employed as an inspection 20 lamp in conjunction with an automobile as it may readily be disposed in a tool box or in other locality where the bulb is apt to be broken unless guarded.

In the preferred embodiment of the invention the casing includes a globular portion and has one or more swinging sections adapted when adjusted to open the casing to serve as reflecting means for the lamp. To simplify the construction and to increase 35 the reflecting surface, the closure of the casing is preferably divided into halves which meet above the lamp bulb when the casing is closed and which may be swung apart to meet below the lamp bulb when the casing 40 is opened.

I will explain my invention more fully by reference to the accompanying drawing showing the preferred embodiment thereof and in which Fig. 1 is a view illustrating 45 the handle structure and casing in longitudinal section and the lamp structure associated therewith in elevation, the casing being closed; Fig. 2 is a view of the structure taken on line 2-2 of Fig. 1, parts of 50 the lighting element being broken away; Fig. 3 is a view in elevation of the upper portion of the portable lamp; Fig. 4 is a sectional view on line 4-4 of Fig. 2; Fig. 5 is a sectional view on line 5-5 of Fig. 3; Fig. 6 is a perspective view illustrating one 55 method of assembling the closure with the

contiguous portion of the casing; Fig. 7 is a detail view showing a modification of the means for assembling the closure and the contiguous portion of the casing; Fig. 8 60 is a view in elevation of the structure shown in Fig. 7; and Fig. 9 is a perspective view of one of the elements appearing in Figs. 7 and 8.

Like parts are indicated by similar characters of reference throughout the different figures.

The lighting element illustrated includes an incandescent lamp bulb 1 assembled with a metallic shell 2 by means of bayonet pins 70 3 entering bayonet slots 4 formed in said shell. The lamp filament 5 is suitably connected with contacts 6 that may, for example, be carried directly upon the base of the lamp or may be otherwise connected 75 with the filament. These contacts are engaged by outwardly spring pressed contacts 7 provided upon an insulating carrier 8 which is fixedly held within and with relation to the shell 2 in any suitable way, as for 80 example by means of an outwardly spring pressed pin 9 registering with aligned openings in the shell 2 and the contact carrier 8. A handle 10 has its forward portion formed with a cylindrical bore so that this part of 85 the handle structure itself serves as a portion of the casing that encloses the lighting element. In the preferred embodiment of the invention this bore is aligned with a cylindrical metallic shell 11 which is brought 90 in fixed relation with the shell 2 by means of the aforesaid outwardly spring pressed pin 9 that also projects into an opening formed in the shell 11 and aligned with the openings in the shell 2 and the contact carrier 95 8 through which the pin 9 extends. To permit the pin to project outwardly beyond the shell 11 to some extent and to prevent the whole lighting element from turning within the handle or holder 10, a longitudinal channel 10' is formed in the handle to receive the outer end of said pin. This channel extends clear through to one end of the handle to permit the pin 9 to be received into and withdrawn from the channel in the 100 process of assembling the shell 11 and the handle or disassembling these elements. The upwardly spring pressed contacts 7 are connected with circuit conductors indicated at 12 and 13. These conductors extend 105 through the bore of a sleeve bolt 14 whose inner end is in threaded connection with the

reduced inner end of the shell 11 and whose outer end is formed with a tool receiving slot 15 by which the bolt may be tightened to draw the shell 11 and the lighting element carried thereby into fixed relation with the handle. To this end the outer end of the shell 11 is formed with the flange 16 that engages the inner end of a casing section 17 which is clamped between the flange 16 and the ferrule 18 by the action of the bolt 14. Said casing section 17 is desirably in the form of a hemispherical cup whose rim is forwardly extended beyond the hemispherical portion of the cup to overlap the closure 15 of the casing. This casing closure is desirably also in the form of a hemispherical cup that is preferably subdivided into two substantially equal portions 19 and 20 both of which are hinged upon the complementary 20 casing section 17 to swing upon a common axis. To this end each of the closure sections 19 and 20 is formed with pintle receiving ears 21 which are assembled by pintles 22. The portions of the closure sections 19 and 25 which meet when the casing is closed thereby is desirably formed with registering notches or recesses 23 and 24 which receive positioning lugs 25, fixed upon and with respect to the cup portion 17 of the 30 casing whereby each closure section 19 is limited in its closing movement that it may just engage the other closure section. The lugs 25 are desirably provided upon the cup-shaped section 17 of the casing by being 35 upon the plates 26 through which the pintles 22 pass, each pintle being suitably headed to maintain it in assembly with the plate 26, the cup 17 and the two eyes 21 through which such pintle passes. Each lug 25 is 40 snugly received in a notch 17' in the casing section 17.

In the embodiment of the invention illustrated in Figs. 1, 2 and 3, the meeting portions of the closure sections 19 and 20 carry 45 the knobbed elements 27 that form a clasp similar to the clasp of a pocket book. When the closure sections are in engagement the knobs engage each other to hold them closed in the position determined by the lug 25. 50 When the casing is to be opened these knobs are twisted apart to permit the separation of the casing sections to occupy a fully reversed position, the cup section 17 of the casing being provided with slots 28 which 55 receive the shanks of the knobbed elements 27, these slots being sufficiently narrow so that said shanks may have tight engagement with the casing section 17 when the closure sections 19 and 20 are in open position so 60 that said closure sections may be held in such position while the lamp is being used. The casing sections 19 and 20 are provided with semi-circular recesses 29 which together receive the outer end of the base of 65 the incandescent lamp bulb 1 when the clo-

sure sections are opened. These closure sections, being hollow and together hemispherical and having their interior surface bright, constitute a reflector when they are adjusted into open position.

When the construction shown in Figs. 7, 8 and 9 is employed the knobbed elements 27 may be dispensed with, for in this alternative construction each lug 25 carries spring fingers 30 that engage beneath closure sections 19 and 20 when these closure sections are closed and are received within the notches 31 in the meeting edges of said closure sections when said closure sections are opened.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. The combination with a lighting element; of a casing therefor having a closure in the form of a cup that is divided substantially in halves, each half of the closure being adjustable from in front of the lighting element. 90

2. The combination with a lighting element; of a casing therefor provided with a cup-shaped section; and a closure in the form of a cup that is divided substantially into halves, each half of the closure being 100 receivable in the aforesaid casing section to uncover the lighting element.

3. The combination with a lighting element; of a casing therefor having a closure in the form of a cup that is divided substantially in halves, each half section of the closure being adjustable from in front of the lighting element; means carried by the casing for limiting the movements of the closure sections in closing directions; and means 105 for holding the closure sections in closed positions.

4. The combination with a lighting element; of a casing therefor provided with a cup-shaped section; a closure in the form of a cup that is divided substantially into halves, each half of the closure being receivable in the aforesaid casing section to uncover the lighting element; means carried by the aforesaid casing section for limiting the movements of the closure sections in closing directions; and means for holding the closure sections in closed positions. 115

5. The combination with a lighting element; of a casing therefor having a closure in the form of a cup that is divided substantially in halves, each half section of the closure being adjustable from in front of the lighting element; means carried by the casing for limiting the movements of the 125

closure sections in closing directions; and means for holding the closure sections in closed positions, the closure sections carrying portions which are engageable with complementary portions upon the casing to hold the closure sections in open position.

6. The combination with a lighting element; of a casing therefor provided with a cup-shaped section; a closure in the form of 10 a cup that is divided substantially into halves, each half of the closure being receivable in the aforesaid casing section to uncover the lighting element; means carried by the aforesaid casing section for limiting 15 the movements of the closure sections in closing directions; and means for holding the closure sections in closed positions, the closure sections carrying portions which are engageable with complementary portions upon 20 the casing to hold the closure sections in open position.

7. The combination with a shell; of a contact carrier within the shell; a holder for said shell formed with a bore that receives said shell and having a longitudinal channel 25 communicating with said bore and extending clear through to one end of the holder; and a pin carried by said shell and projecting into said channel.

8. The combination with a shell; of a contact carrier within the shell; a holder for said shell formed with a bore that receives said shell and having a longitudinal channel 30 communicating with said bore and extending clear through to one end of the holder; and an outwardly sprung pressed pin carried by said shell and projecting into 35 said channel.

In witness whereof, I hereunto subscribe my name this 30th day of March, A. D. 1921. 40

HARRY A. DOUGLAS.
